(57) **CLAIM**

I claim the ornamental design for the digital video disk player, as shown in the accompanying figures.

DESCRIPTION

FIG. 1 is a perspective view of a digital video disk player showing my new design;

FIG. 2 is rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view of the second embodiment of FIG. 1;

FIG. 8 is a rear elevational view thereof;

FIG. 9 is a top plan view thereof;

FIG. 10 is a bottom plan view thereof;

FIG. 11 is a right side elevational view thereof; and,

FIG. 12 is a left side elevational view thereof.

The broken line showing on the drawing disclosure is for illustrative purposes only and forms no part of the claimed design.
